CLAIM

The ornamental design for a duster with handle, as shown and described.

DESCRIPTION

FIG. 1 is a view showing the top of the design of the present invention.

FIG. 2 is a view showing the bottom of the design of the present invention.

FIG. 3 is a side view showing the design of the present invention.

FIG. 4 is a view showing the opposite side of that which is shown in FIG. 3.

FIG. 5 is an enlarged rear view of the design of the present invention.

FIG. 6 is a front view of the design of the present invention; and,

FIG. 7 is a perspective view of the design of the present invention.

The broken line outline representing the dusting element is for illustrative purposes only and forms no part of the claimed design.
